UNITED STATES PATENT OFFICE.

JULIUS N. CAYO, OF GARY, INDIANA.

CAN-OPENER.

1,189,058.

Specification of Letters Patent. Patented June 27, 1916.

Application filed September 24, 1915. Serial No. 52,486.

To all whom it may concern:

Be it known that I, JULIUS N. CAYO, a citizen of the United States, residing at Gary, in the county of Lake and State of Indiana, have invented new and useful Improvements in Can-Openers, of which the following is a specification.

This invention is an improved can opener especially adapted for use in cutting a circular hole in a can, the object of the invention being to provide an improved device of this character which is cheap and simple, which may be readily operated, and which is not likely to get out of order.

15 The invention consists in the construction, combination and arrangement of devices hereinafter described and claimed.

In the accompanying drawings:—Figure 1 is a vertical sectional view of a can opener 20 constructed in accordance with my invention. Fig. 2 is an inverted plan of the same. Figs. 3—4 are detail views.

In the embodiment of my invention I provide a circular housing 1 which is 25 formed with an annular base flange 2, is made of sheet metal, and is provided at opposite sides with offsets 3. A shaft 4 extends across the lower portion of the housing, is mounted in bearings 5 in the wall 30 of the housing, is provided with a spur gear 6 and also has a crank handle 7 at one end to enable said shaft to be readily threaded.

A circular plate 8 is fitted in the base of 35 the housing, to close the lower end thereof, is provided with an opening 9 through which one side of the gear 6 extends, and is also provided with spurs 10 which are formed integrally therewith and arranged 40 at opposite sides thereof and are provided with shoulders 11 which fit in the offsets 3 of the base flange of the housing. The plate 8 is secured to the base flange of the housing by bolts or other suitable fastening devices 45 12. I also provide a circular cutter plate 13 which is arranged on the outer side of the plate 8 and is mounted for rotation on a centrally arranged spur 14 which is secured to the plate 8. The cutter plate has gear open-

50 ings 15 for the reception of the spurs of the gear 6 so that the cutter plate may be revolved by said spur gear, as will be understood. At one side of the revoluble cutter plate is a knife 16 which is integral thereto 55 with and arranged at right angles thereto

and is provided with suitable sharpened edges 17.

To operate the can opener the same is placed on the top or bottom of a can and its spurs 10 and the center spur 14 are driven 60 through the can so as to secure the device to the can and hold it in place while being operated. The shaft is then turned by means of its crank handle, causing the cutter plate, which is geared to said shaft, which 65 is hereinbefore stated to be revolved so that the knife 16 cuts a circular opening in the can.

Having thus described my invention, I claim:—

1. A can opener of the class described comprising a sheet metal housing open at one side and provided at said open side with an annular flange having offsets, a plate secured to said flange of the housing, extending across and closing the open side thereof and having spurs arranged at right angles thereto and provided with shoulders fitted in said offsets, a revoluble cutter plate mounted on the first named plate and provided with a center spur and also a knife, and a shaft extending across and mounted for rotation in the housing, and provided with a crank handle, the said shaft being 70 75 80 85 geared to the cutter plate to rotate the latter.

2. An can opener of the class described comprising a housing open at one side and provided at said open side with an annular flange having offsets, a plate secured to said flange of the housing, extending across and closing the open side thereof and having spurs arranged at right angles thereto and provided with shoulders fitted in said offsets, a revoluble cutter plate mounted on the first named plate and provided with a center spur and also a knife, and a shaft extending across and mounted for rotation in the housing, and provided with a crank handle, the said shaft being 90 95 100 105 geared to the cutter plate to rotate the latter, the said center spur being secured to the first named plate and forming the axis for the revoluble cutter plate and said knife being formed integrally with the cutter plate.

In testimony whereof I affix my signature in presence of two witnesses.

JULIUS N. CAYO.
